UNITED STATES PATENT OFFICE

GEORGE D. HAUSER, OF UTICA, NEW YORK, ASSIGNOR TO UTICA PRODUCTS, INC., OF ⁶⁵
UTICA, NEW YORK, A CORPORATION OF NEW YORK

RECEPTACLE

Application filed February 18, 1929. Serial No. 340,788.

My invention relates to receptacles and more particularly to receptacles for waste or refuse.

One of the objects of the invention is to provide a receptacle of the character referred to which is simple and strong in construction. Another object of the invention is to construct the receptacle so that refuse can be readily placed therein or the receptacles emp-
10 tied when the receptacle is placed against a wall. A further object is to provide im-
proved means for draining off water which may enter the receptacle through the door thereof.

15 Other features and advantages will appear more fully from the following detailed description and appended claims.

The drawings forming a part of this speci-
20 fication illustrate one embodiment of the in-
vention.

In the drawings,

Figure 1 is a front elevation of the upper portion of the receptacle.

Figure 2 is a vertical cross section thereof
25 taken on line 2—2 of Fig. 3.

Figure 3 is a vertical cross section taken on line 3—3 of Fig. 2.

Figure 4 is a vertical cross section taken on line 4—4 of Fig. 2.

30 Figures 5 and 6 are enlarged sectional views showing details of construction.

The receptacle comprises a lower or body portion 1 having a cover portion 2 mounted thereon. The cover portion is formed with a rear wall 3 arranged in a vertical plane, a front wall 4 inclined upwardly and towards the rear wall 3, side walls 5 and 6 arranged in vertical planes and a horizontal top wall 7. The front wall 4 is provided with a door opening having an inwardly directed flange 8 along the upper and side edges thereof. Arranged to close this opening is a door 9. The door as shown is formed with a forward closure portion, the upper edge of which is hinged as shown at 10. In order to yield-
40 ingly hold the door in closed position, it is formed with a counterweight portion 11 which extends inwardly of the receptacle from the upper edge of the closure portion
45 at a suitable angle to the latter, preferably

a right angle. This counterweight portion, as shown, has secured along the entire inner edge thereof a weight 12 to assist in holding the door closed. To strengthen the door a brace 14 is provided. This brace as shown extends from the weight 12 to the lower part of the closure portion of the door, its ends being secured to the door as by welding. By this construction the downward pressure of the part 11 and weight 12 is transmitted to the closure portion 9 of the door through the brace 14 and a very strong rigid door construction is obtained. The door as shown is formed of sheet metal, the part 11 being integral with the part 9. Fig. 3 shows the door open in solid lines and closed in dotted lines. Referring to this figure, it will be seen that when the door is wide open the counterweight portion 11 is substantially horizontal so that, together with the weight 12, it exerts a maximum tendency to close the door. A rubber buffer 4' is secured to the front wall 4 to act as a cushion for the door when closing.

As doors in receptacles of the character referred to occasionally become damaged, I provide a construction whereby the door may be readily detached and a new one substituted therefor. To this end a pivot rod 10 is rigidly secured, as by spot welding, to the door and has projecting pivot portions 10a and 10b which turn in brackets 15 and 16 which are detachably secured to the front wall 4 of the top of the receptacle, as by screw bolts 17. With this construction, when it is de-
35 sired to replace an old door with a new one it is simply necessary to disconnect one of the brackets 15 or 16 by removing the screw bolts 17 whereupon the opposite end of the pivot 10 can be slid out of the other bracket and the door detached. The proper end of the pivot 10 of the new door is then inserted in the bracket which is secured in place, and the other bracket placed upon the opposite end of the pivot and secured in place to the front wall 4 of the top of the receptacle by means of the screw bolts 17. To facilitate holding the pivot rod 10 in place with respect to the door, I preferably form the door with straps 18 which are stamped in-
40 45 50 55 60 65 70 75 80 85 90 95 100

wardly from the door and are arranged to form loops through which the pivot rod passes and inside of which it fits.

As receptacles of the character referred to are sometimes exposed to the rain, it is desirable to provide means whereby rain or other moisture entering the top of the receptacle through the door opening may be conveniently drained off. To this end I construct the top portion of the receptacle so that it projects forwardly of the front wall of the body portion of the receptacle a certain distance so as to provide between the top and bottom portions of the receptacle an outlet drain opening 19 (Figs. 3 and 4). The lower portion of the door is provided with an apron 20 which directs moisture running down the door outwardly through the drain opening 19. To facilitate the drainage of water collecting on the door, I have formed the latter with a horizontal gutter 21 and vertical gutters 22 leading from the gutter 21 and discharging upon the apron 20. The gutters 21 and 22 are preferably arranged immediately behind the peripheral door flange 8, the latter projecting to a slight extent into the gutters. With this arrangement an effective construction is provided to prevent the entrance of moisture into the body of the receptacle and to lead off through the drain opening 19 such moisture as may impinge upon the door.

To permit ready access to the interior of the body portion 1 of the receptacle the top 2 thereof is hinged thereto, as by hinge 24, so as to be movable laterally to open position. The hinge as shown is of very simple construction, consisting of a plate 25 (see Figs. 4 and 6) which has a portion extending through a horizontal opening 26 extending through the body portion 1 near the top thereof. This inwardly extending portion 27 has at its inner ends laterally projecting pintle or pivot portions 28 which are arranged to bear against the inside wall of the body portion 1 when the cover is opened. This construction of hinge permits a very simple and economical assembly of the top and body portions. The hinge 25 is formed with its pintle portions extending longitudinally thereof as shown in dotted lines in Fig. 4. As so formed it is secured to the cover portion and passed through the opening 26 whereupon the pintle portions 28 are bent laterally to operative position by means of a hammer or other suitable means. A flange 34 is secured to that side wall of the top which is opposite to the side wall to which the hinge 24 is secured. This flange is arranged to rest on the upper edge of the body 1 of the receptacle to act as a stop for the cover portion when the latter is in closed position. As the top portion of the receptacle extends outwardly beyond the lower portion, as shown in Fig. 6, the lower edge 30 thereof

is arranged to abut against the body portion of the receptacle, as shown in dotted lines in Fig. 6, to limit the opening movement of the top portion of the receptacle. To reinforce the lower edge of the top portion 2 and the upper edge of the bottom portion 1 of the receptacle, these edges may have secured thereto suitable bands as shown at 31 and 32 respectively.

By reason of the shape of the receptacle and the arrangement of the door 9 and the hinge 25 between the top and body portions, the receptacle may be conveniently arranged with its back against a wall and operated in that position both to place refuse or waste into the receptacle through the door 9 or to tilt the top 2 laterally to remove the refuse collected in the receptacle. If desired, a detachable bag or container may be supported in the body of the receptacle by suitable means such as the hooks 33.

It is to be understood that various changes may be made in the detailed construction described without departing from the spirit and scope of the invention as defined by the appended claims.

I claim:

1. A receptacle comprising a body portion and a top therefor provided with an inclined door, a portion of said top being spaced from said body portion to provide a drain opening and said door being provided with means for directing water impinging thereon out of the container through said opening. 95

2. A receptacle comprising a body portion and a top therefor provided with an inclined door, a portion of said top being spaced from said body portion to provide a drain opening and said door being provided with downwardly extending gutters and an apron at the bottom thereof for directing water impinging thereon out of the container through said opening. 100 105

3. A receptacle comprising a body portion, a top therefor having a portion spaced from said body portion to provide a drain opening, said top portion having an inclined wall provided with a door opening having an inwardly directed peripheral flange at the top and sides thereof, a door for said last named opening, said door having a groove toward which said flange is directed and an apron for directing water impinging on the door outwardly through said drain opening. 110 115

4. In a receptacle having a door opening, a door comprising a metal sheet bent intermediate its ends to form a closure portion and a counterweight portion, loops struck out from said sheet and its bend and projecting inwardly, and a rod supported within said receptacle and passing through said loops. 120 125

5. A receptacle comprising a body portion, a top portion hinged thereto to permit swinging of the top portion to one side of the body portion, a section of said top portion being 130

spaced from said body portion to provide a drain opening, and a counterweighted door in said top portion, said door being provided with means for directing water impinging
5 thereon through said opening.

6. A receptacle having a top provided with a flat vertical rear wall and a front wall inclined toward said rear wall, a door opening in the inclined portion of said front wall, a
10 door comprising a metal sheet bent intermediate its ends to form a closure portion and a counterweighted portion, loops struck out from said sheet at its bend and projecting inwardly, and a rod supported within said receptacle and passing through said loops, said closure portion being of greater area than
15 said opening.

In testimony whereof, I have signed my
20 name to this specification.

GEORGE D. HAUSER.
